UNITED STATES PATENT OFFICE

2,462,804

VOLTAGE MULTIPLIER

Don Canady, Cincinnati, Ohio, assignor to Dayton
Acme Company, Cincinnati, Ohio, a corpora-
tion of Ohio

Application January 14, 1947, Serial No. 721,967

1 Claim. (Cl. 171—97)

1

This invention relates to improved simplified means to increase direct current voltage. Heretofore expensive equipment was needed to increase the voltage such as is needed in photoelectric cell pickup for sound projection.

The object of my invention is to provide a unit for alternately collecting the applied voltage in a plurality of condensers and alternately discharging the voltage from the condensers to multiply the voltage discharged.

A further object is to provide rotary means for alternately collecting and discharging the applied voltage.

My invention will be further readily understood from the following description and claim and from the drawings in which latter:

Fig. 1 is a plan view of one form of my improved device.

Fig. 2 is a detail section, taken in the plane of the line 2—2 of Fig. 1.

Fig. 3 is a diagrammatic view of the same.

Fig. 4 is a diagrammatic view of a modification of my invention.

Fig. 5 is a wiring diagram, showing the collecting circuit.

Fig. 6 is a wiring diagram, showing the discharge circuit.

Fig. 7 is a wiring diagram of the modification shown in Fig. 4.

Fig. 8 is a plan view of a further modification of my invention, taken in the plane of the irregular line 8—8 of Fig. 9.

Fig. 9 is a vertical section of the same, taken in the plane of the line 9—9 of Fig. 8.

Fig. 10 is a detail section, taken in the plane of the line 10—10 of Fig. 9.

Fig. 11 is a wiring diagram of the same.

My improved structure comprises a rotary member 15 of insulating material mounted on a shaft 16 which can be suitably driven from any power source. Collector rings 17 and 18 are secured to the insulated member and split rings 19, 20, 21, 22, 23, 24, 25, and 26 which are formed in two parts with gaps between the ends of the respective rings. A pair of rings 27 and 28 are arranged to discharge the increased voltage. Brushes 30, 31, 32, 33, 34, 35, 36, and 37 contact the respective collector rings with the power source connected to brushes 30 and 31. The ring 17 is connected to the split rings 19 and 23 by a connection 38 and the ring 18 is connected to the split rings 21 and 25 by a connection 39. The split ring 20 is connected to the discharge ring 28 by a connection 40 and the rings 22 and 24 are connected together by a connection 41 with

2

the ring 26 connected to the discharge ring 27 by a connection 42. The brushes 32 and 33 are connected together with a condenser 43 interposed in the line 44. The brushes 34 and 35 are connected together with a condenser 45 interposed in the line 46. The brushes 36 and 37 have feed lines 47 and 48 extending therefrom with a condenser 49 across the lines.

Assuming the source voltage is 400 volts D. C. 10 and the brushes 32 and 33 are contacting the rings 19 and 21 and the brushes 34 and 35 are contacting the rings 23 and 25 the condensers 43 and 45 are in parallel relation and will each become loaded with 400 volts. As the rotary member rotates the brushes 32 and 33 will contact the rings 20 and 22 and the brushes 34 and 35 will contact the rings 24 and 26 thus placing the condensers 43 and 45 in series whereby they will discharge 800 volts into the condenser 49 which 15 can then be discharged into the line. In Fig. 1 I have shown two units coupled together in which case if the source voltage is 400 volts D. C., the final discharge will be 1600 volts D. C.

In the modification shown in Fig. 4 a pair of 20 spaced ring members 50 and 51 are included between the ends of rings 22' and 24', with a resistance 52 across the two ring members, which slows down or causes a delayed action to the 25 passage of the voltage. This is also shown in the wiring diagram of Fig. 7.

The device shown in Figs. 8 to 11 inclusive operates in a similar manner to that shown in Fig. 1 except in this structure a cam 75 rotates to alternately charge the condensers 76 and 77 by 30 means of the contacts 78 contacting the contacts 79 and to discharge the voltage from the condensers 76 and 77 into the condenser 80 when 35 contacting the contacts 81. Thus when the cam is in the position shown in Fig. 9 the condensers 76 and 77 are connected parallel and when the contacts 78 are contacting the contacts 81 the condensers are in series to discharge into the condenser 80.

Having thus fully described my invention, what 40 I claim as new and desire to secure by Letters Patent, is:

A voltage multiplier comprising a rotary member, a pair of collector rings on one end of said member, a second pair of discharge collector 45 rings on the other end of said rotary member, split rings between said pairs of rings, brushes contacting all of said rings, said brushes contacting said first named pair of collector rings connected to a source of electrical supply, said 50 brushes contacting said intermediate split rings

connected in pairs with a condenser interposed therein, said second pair of discharge collector rings having brushes having a condenser connected thereacross, and means connecting said split rings to said full rings whereby during the revolution of said rotary member said intermediate condensers will be alternately connected in parallel to said supply and alternately connected in series to said discharge collector rings.
